UNITED STATES PATENT OFFICE

2,384,461

ENGINE

Waldo G. Gernhardt, Detroit, Mich., assignor to
 Briggs Manufacturing Company, Detroit, Mich.,
 a corporation of Michigan

Application January 7, 1944, Serial No. 517,381

19 Claims. (Cl. 123—80)

This invention relates to internal combustion engines and particularly to engines of the type having rotatable valves associated with the cylinders thereof and usually mounted in the cylinder heads of the engines. The present invention has particular although not exclusive application to an internal combustion engine of the kind in which the rotatable valve in the head, preferably although not necessarily of the kind which rotates continuously in one direction, is formed with substantially all or at least the major portion of the combustion chamber and is generally conical or frusto-conical in shape. The combustion chamber within the rotor or rotary valve has an opening at one end leading to the cylinder and a second opening preferably at a side thereof adapted to communicate during operation with an outlet or inlet passage, or both, as the case may be, and the combustible charge within the combustion chamber is fired preferably by spark ignition.

The present invention contemplates as one of its important objects the efficient cooling of engines of the foregoing type as also the provision of means for controlling the expansion of portions of the cylinder head adjacent the rotatable valve so as to maintain more closely or accurately the desired operating clearances between the valve and related bearing surfaces on the cylinder head.

A further object of the invention is to provide an engine having a rotatable valve and improved means for controlling the relative expansion of the valve and cylinder head due to heating of associated portions thereof during operation.

Another object of the invention is to provide an engine having a cylinder, cylinder head and a rotatable valve in the head, such as a generally frusto-conical valve, and in which means are provided for maintaining closely predetermined operating clearances between the valve and head, especially where the valve and head are made of metals or metal alloys having different thermal expansion rates.

It is also an object of the invention to provide an engine having a cylinder head and a valve rotatable therein and having a different, such as a smaller, coefficient of expansion than the head and in which means is provided whereby the rate of expansion of the head will be substantially the same as the valve at certain bearing localities where it is desirable to maintain uniform operating clearances between the cooperating bearing surfaces of the valve and head.

Other objects of this invention will appear in

the following description and appended claims, reference being had to the accompanying drawing forming a part of this specification wherein like reference characters designate corresponding parts in the several views.

5 Fig. 1 is a fragmentary sectional elevation illustrating a portion of a multi-cylinder engine embodying the present invention.

10 Fig. 2 is a transverse section taken substantially through lines 2—2 of Fig. 1 looking in the direction of the arrows.

15 Fig. 3 is an enlarged fragmentary section illustrating the portion of Fig. 1 appearing within the circle.

20 Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation.

25 Referring to the drawing, the present engine comprises a cylinder 28 within which a suitable piston 24 is mounted for reciprocation. The piston is connected in the usual manner through a wrist pin 22 to the crankshaft (not shown) of the engine. Surrounding the cylinder 28 is a cylindrical jacket 24 which is rigidly secured to the crankcase or forms substantially a portion of the crankcase of the engine. This jacket member 24 extends substantially the height of the cylinder and is spaced from the wall of the cylinder to provide a water cooling space or chamber 25 extending entirely around the cylinder.

30 The engine is provided with a cylinder head 26 which is cast to provide a valve housing portion 27 provided with a generally frusto-conical cavity or recess, as hereinafter described, for receiving the rotary valve. The cylinder head is also cast to provide a cylinder head jacket 28 spaced from the valve housing 27. The liquid cooling space or chamber 25 forms a continuation of the chamber 28. When the cylinder head is assembled the lower edge of the jacket portion 28 is drawn down tightly against the upper edge of the cylinder jacket 24, there being a gasket 30 interposed between the juxtaposed surfaces of these portions adapted to be compressed to provide a liquid-tight joint.

35 The lower or inner edge of the valve housing portion 27 of the cylinder head is formed with an annular boss or thickened portion 31, and this

ortion is formed with an annular groove or recess 32 to receive an expansion control ring 33. This ring preferably has a tight or press fit within the recess or groove 32 and the outer face of the ring extends substantially flush with the outer face of the enlarged portion 31 of the valve housing 27. The upper edge of the cylinder 29 extends in abutting relation to that portion of the lower edge of the valve housing 27 which lies inwardly of the expansion control ring 33, and interposed between the cylinder and valve housing is an annular gasket 34. This gasket may be of the copper-asbestos type capable of sustaining high temperatures and pressure, and when the cylinder head is drawn down tightly this gasket will provide a liquid and gas-tight joint. In order that a gasket 34 of maximum width may be used and at the same time to avoid excessive restriction of the liquid passage between the chambers 28 and 29, the expansion control ring 33 sets entirely into the recess 32 in the valve housing and notched at 33a around its lower inner edge to provide clearance for the gasket ring 34. The cylinder head is formed with a series of fins or ribs 36 and 37 bored to receive bolts 38 extending from bosses (not shown) on the jacket member 24 which, as stated, is fixed to the crankcase. The cylinder head may be drawn down tightly to the crankcase or jacket 24 by suitable nuts applied to the upper ends of the bolts 38, thus connecting the jackets 24 and 28 tightly together at the water tight joint formed by the gasket 30.

The cylinder head is formed with a generally frusto-conical recess 40 within which is mounted a rotatable valve or rotor 41 which is also of generally frusto-conical construction having tapering outwardly converging walls corresponding generally in shape to the inner walls of the recess 40. The bottom or inner wall 41a of the valve is preferably tapered so as to correspond substantially to the taper of the piston head, the construction being such that the piston head will approach very closely the bottom of the valve 41 when the piston is at the outer end of its stroke. The valve member 41 is formed with a side port communicating with the combustion chamber and adapted to register successively during rotation of the valve with a spark plug 44, an exhaust passage or conduit 45, and an intake port or passage 46 in the cylinder head, the direction of rotation of the valve being indicated by arrow in Fig. 3. As also shown in this figure, liquid coolant chamber 28 has extensions 28a in the cylinder head extending substantially under the valve member 41 and also extending inward and in the height of the outer walls of the exhaust and intake passages 45 and 46. Another portion 28b of the coolant chamber extends through the dividing wall between these passages. In this construction it will be seen that substantially all portions of the cylinder, cylinder head, valve and intake and exhaust passages, which are subjected to heating during operation, are exposed to the cooling effect of the liquid circulated through the water jackets. The coolant is preferably introduced into the lower end of chamber 28, circulated upwardly through the communicating chambers, which have a common outlet in the cylinder head.

In addition to the side port 43 the valve 41 has a central port or opening 47 at its inner end communicating with the cylinder. The valve member is also formed with a cooling chamber 48 extending entirely around the combustion cham-

ber of the valve member. This cooling chamber is adapted to receive any suitable cooling medium such, for example, as metallic sodium, which is sealed into the chamber by means of an expanding plug 48a.

In the present embodiment the valve or rotor 41 is driven at one-half engine or crankshaft speed. It is provided with a projecting stem 49 through the medium of which the driving mechanism for the valve is connected. The valve housing portion 27 of the cylinder head is provided with an annular recess 50 in its outer end through which the valve stem 49 extends. Within this recess is located a cup-shaped spring retainer member 51 adapted to receive a compression spring 52 surrounding the valve stem 49. The outer end of the spring engages a steel coupling disk 53. This disk is formed centrally thereof with an annular set of teeth 54 meshing with corresponding teeth formed on the end of the valve stem 49. The valve stem is tapped to receive a threaded stud or bolt 56 which carries a nut 56a engageable with the coupling disk 53 and adapted to be tightened to draw down the disk and maintain its teeth 54 in constant mesh with the teeth on the outer end of the valve stem. The spring 52 is, therefore, held under constant compression so as to yieldingly hold the valve upwardly within the frusto-conical recess 40 in the valve housing. The strength of this spring and the amount of preloading thereof is such that the effort exerted by the spring to raise the valve within the valve housing is sufficient to substantially offset or equal the effort exerted during the suction stroke of the piston to draw the valve downwardly and away from its seat.

The coupling disk 53 is provided with external teeth 55 meshing with internal teeth 57a on a ring gear 57. This gear in turn has external teeth 57b meshing with the teeth of a valve driving gear 58 secured to a longitudinally extending top shaft 61. The cylinder head is formed with a housing 59 provided with a removable closure 60 for housing the driving mechanism located in the cylinder head. The top shaft 61 may be driven from the crankshaft of the engine in the manner shown and described in application Serial No. 515,479, filed December 24, 1943.

The valve member is also preferably provided with an exterior relief area 70 extending entirely around the valve and substantially the height of the side port 43. This annular relief area may be formed either in the valve or in the wall 40 of the valve housing and may be constructed and serve the purposes in accordance with my copending application Serial No. 495,260, filed July 19, 1943.

In accordance with the present invention the ring 33 is adapted to restrain or control the expansion of the wall portion 31 of the cylinder head during operation of the engine so as to maintain within close limits the desired operating clearance between the inner end of the valve and the valve housing 27. It will be understood that the bearing surfaces of the valve 41 and housing 27 above and below the relief area 70 are suitably lubricated in order to maintain a film of oil between these surfaces. It is, therefore, important that the operating clearance between these surfaces be held constant and be prevented from increasing appreciably since otherwise there will result an undesirable loss of lubricating oil due to oil being drawn into the cylinder during the suction stroke of the piston.

The expansion control ring 33 is preferably

75

formed of a metal or metal alloy selected so that by virtue of its differential expansion rate the head portion 31 will expand at substantially the same rate as the adjacent portion of the cone valve. Where the head is made of an aluminum alloy the ring 33 will be made of a metal or metallic alloy having a coefficient of expansion less than that of the aluminum alloy of the head but not less than that of the valve. For example, if the cylinder head is formed of aluminum and the valve of cast iron, the ring may be made of steel. In such case the expansion rate of the ring will be considerably less than that of the head but somewhat greater than that of the valve. This is desirable since the valve becomes hottest at its inner end and tends, on account of its higher temperature, to expand at this locality more than the adjacent portion 31 of the head. Thus, with an aluminum head and a valve of cast iron or other ferrous metal, it is preferred that the ring 33 have a thermal expansion rate less than that of the head but somewhat greater than that of the valve, especially in view of the fact that the ring is maintained at a lower temperature by being exposed directly to the coolant in the jacketed chamber 28.

I claim:

1. In an internal combustion engine, a cylinder, a cylinder head, a rotatable valve in said head, said valve and head having different coefficients of thermal expansion, said valve and head having adjacent wall portions in operative engagement, and means for varying the rate of expansion of said portion of the head so as to conform more closely to the rate of expansion of said portion of the valve.

2. In an internal combustion engine, a cylinder, a cylinder head, a rotatable valve in said head, said valve and head having different coefficients of thermal expansion, said valve and head having adjacent wall portions in operative engagement, and means for reducing the rate of expansion of said portion of the head so as to conform more closely to the rate of expansion of said portion of the valve.

3. In an internal combustion engine, a cylinder, a cylinder head, a rotatable valve in said head, said valve having a lesser coefficient of thermal expansion than the head, said valve and head having adjacent wall portions in operative engagement, and means for restraining expansion of said portion of the head relative to said adjacent portion of the valve.

4. In an internal combustion engine, a cylinder, a cylinder head, a rotatable valve in said head, said valve having a lesser coefficient of thermal expansion than the head, said valve and head having adjacent wall portions in operative engagement, and means for reducing the rate of expansion of said portion of the head so as to conform more closely to the rate of expansion of said adjacent portion of the valve.

5. In an internal combustion engine, a cylinder, a cylinder head, a rotatable valve in said head, said valve and head having different coefficients of thermal expansion, said valve and head having adjacent wall portions in operative engagement, and means carried by the head for varying the rate of said expansion of a portion of the head so as to conform more closely to the rate of expansion of said adjacent portion of the valve.

6. In an internal combustion engine, a cylinder, a cylinder head, a rotatable valve in said

head, said valve having a lesser coefficient of thermal expansion than the head, said valve and head having adjacent wall portions in operative engagement, and means carried by the head for restraining expansion of said portion of the head relative to said adjacent portion of the valve.

7. In an internal combustion engine, a cylinder, a cylinder head, a rotatable valve in said head, said valve having a lesser coefficient of thermal expansion than the head, said valve and head having adjacent wall portions in operative engagement, and an expansion control ring engaging said wall portion of the head for restraining expansion thereof relative to said adjacent portion of the valve.

8. In an internal combustion engine, a cylinder, a cylinder head, a rotatable valve in said head, said valve having a lesser coefficient of thermal expansion than the head, said valve and head having adjacent wall portions in operative engagement, and an expansion control ring having a lesser coefficient of expansion than the head for restraining expansion of said portion thereof relative to said adjacent portion of the valve.

9. In an internal combustion engine, a cylinder, a cylinder head, a rotatable valve in said head, said valve and head having adjacent walls in operative engagement, and an expansion control ring engaging said wall of the head for varying its rate of thermal expansion with respect to that of the valve.

10. In an internal combustion engine, a cylinder, a cylinder head, a rotatable valve in said head, said valve and head having adjacent walls in operative engagement, and an expansion control ring engaging said wall of the head and carried thereby for varying its rate of thermal expansion with respect to that of the valve.

11. In an internal combustion engine, a cylinder, a cylinder head, a rotatable valve in said head, said valve and head having adjacent walls in operative engagement, and an expansion control ring engaging said wall of the head for reducing its rate of thermal expansion with respect to that of the valve.

12. In an internal combustion engine, a cylinder, a cylinder head, a rotatable valve in said head, said valve and head having adjacent walls in operative engagement, and expansion control means engaging said wall of the head for modifying its rate of thermal expansion with respect to that of the valve.

13. In an internal combustion engine, a cylinder, a cylinder head, a rotatable generally frustoconical valve in said head, said valve and head having adjacent walls in operative engagement, and expansion control means engaging said wall of the head adjacent the inner end of the valve for modifying its rate of thermal expansion with respect to that of the valve.

14. In an internal combustion engine, a cylinder, a cylinder head, a rotatable valve in said head, said valve and head having adjacent walls in operative engagement, and expansion control means engaging said wall of the head and having a lesser coefficient of thermal expansion than the head for modifying its rate of thermal expansion with respect to that of the valve.

15. In an internal combustion engine, a cylinder, a cylinder head, a rotatable valve in the head, and expansion control means formed of metal having a lesser coefficient of thermal expansion than the head and a greater coefficient

of thermal expansion than the valve for restraining expansion of the head relatively to the valve.

16. In an internal combustion engine, a cylinder, a cylinder head having a portion provided with a generally frusto-conical cavity, a generally frusto-conical valve in said cavity, said cylinder and valve being formed of ferrous metal and said cylinder head being formed of metal having a greater coefficient of thermal expansion, and means for restraining lateral expansion of said head at the locality of its bearing engagement with the valve at the inner end of the latter, said means comprising a ring engaging the head and formed of different metal than the head.

17. In an internal combustion engine, a cylinder, a cylinder head, a rotatable valve in the head, a liquid coolant jacket surrounding the valve and its bearing portion in the head, and an expansion control ring carried by the head adjacent the inner end of the valve and exposed to the coolant in said jacket.

5 18. In an internal combustion engine, a cylinder, a cylinder head, a rotatable generally frusto-conical valve in the head, a liquid coolant jacket surrounding the valve and its bearing portion in the head, and an expansion control ring carried by the head at the locality of its bearing engagement with the wider end of the valve and exposed to the coolant in said jacket.

10 19. In an internal combustion engine, a cylinder, a cylinder head, a rotatable generally frusto-conical valve in the head, a liquid coolant jacket surrounding the valve and its bearing portion in the head, and an expansion control ring carried by the head at the locality of its bearing engagement with the wider end of the valve and exposed to the coolant in said jacket, said ring being formed of metal having a different coefficient of expansion than the head.

of thermal expansion than the valve for restraining expansion of the head relatively to the valve.

16. In an internal combustion engine, a cylinder, a cylinder head having a portion provided with a generally frusto-conical cavity, a generally frusto-conical valve in said cavity, said cylinder and valve being formed of ferrous metal and said cylinder head being formed of metal having a greater coefficient of thermal expansion, and means for restraining lateral expansion of said head at the locality of its bearing engagement with the valve at the inner end of the latter, said means comprising a ring engaging the head and formed of different metal than the head.

17. In an internal combustion engine, a cylinder, a cylinder head, a rotatable valve in the head, a liquid coolant jacket surrounding the valve and its bearing portion in the head, and an expansion control ring carried by the head adjacent the inner end of the valve and exposed to the coolant in said jacket.

5 18. In an internal combustion engine, a cylinder, a cylinder head, a rotatable generally frusto-conical valve in the head, a liquid coolant jacket surrounding the valve and its bearing portion in the head, and an expansion control ring carried by the head at the locality of its bearing engagement with the wider end of the valve and exposed to the coolant in said jacket.

10 19. In an internal combustion engine, a cylinder, a cylinder head, a rotatable generally frusto-conical valve in the head, a liquid coolant jacket surrounding the valve and its bearing portion in the head, and an expansion control ring carried by the head at the locality of its bearing engagement with the wider end of the valve and exposed to the coolant in said jacket, said ring being formed of metal having a different coefficient of expansion than the head.
